DEVICE FOR FIXING GLASSES

Auguste Magis, Paris, France

Application February 16, 1932, Serial No. 593,334
In France February 21, 1931

4 Claims. (Cl. 108—16)

Whatever may be the rapidity with which glasses can be set by means of putty, and the low cost of that operation, the difficulties of upkeep make that method of fixing glasses really expensive, so that, all things being considered, it is less expensive to have recourse to glass settings that do not require any putty.

Several solutions of the problem have already been proposed, which are generally satisfactory from the viewpoint of water-tightness, but present several drawbacks, either because they are expensive and require sash irons having a special section, or because they involve the use of metallic bands having but a very low resistance, which require a special care for setting them and do not avoid the annual upkeep.

The object of my invention is to provide a joint covering arrangement adapted to be used in connection with usual sash irons and characterized by the use of metallic bands capable of resisting the atmospheric agents, and sufficiently rigid for exerting upon the glass, when said bands are secured, by means of bolts, to the sash irons, a suitable clamping and to ensure perfect water-tightness, without using any putty, glue or similar body.

The arrangement according to my invention further has the advantage of being readily and quickly set. When prepared in advance in the workshop, it does not require any work at the place where it is to be utilized.

I preferably make use, for the manufacture of the joint covering according to my invention, bands of zinc, aluminium, galvanized steel, or any other metal or alloy capable of withstanding variations in the weather, easily bent, but having a rigidity and an elasticity sufficient for maintaining the glass by the tightening of the fixation bolts, without however creating any danger of breaking under the effect of an excessive clamping.

A preferred embodiment of my invention will be hereinafter described with reference to the accompanying drawing, given merely by way of example, and in which:

Fig. 1 is a transversal sectional view of an assemblage including the device according to my invention;

Fig. 2 is a corresponding plane view;

50 Fig. 3 is a sectional view on the line III—III of Fig. 1.

Adverting to Fig. 1, the steel T-shaped iron 1 of the ordinary type is provided with two adjacent lateral bands 2, 2, which are applied

and are curved in the shape of gutters so as to form a support for the glasses and also collect and evacuate outwardly any water which might have penetrated under the glasses past the edges thereof. Instead of being distinct as shown in Fig. 1, said bands might form a single piece passing over the web of the iron. Band 3 acts as a cap covering the web of the iron and lateral bands 2, 2. It will be so bent that when it is fixed to the iron through bolts 5, its curved edges exert a pressure upon glasses 4, 4 so as to hold them in position and, at the same time, to form, against them, a sufficiently efficient joint. Owing to the elasticity of band 3, its pressure upon glasses 4, 4 can never be exaggerated, whatever the tightening of the bolts may be. This more or less strong tightening makes it possible to adjust at will the pressure exerted by band 3 upon glasses 4—4, and the pressure exerted by the latter on lateral bands 2, 2, due to its shape and to its elasticity.

The fixation bolts 5 are preferably provided with washers 6, 6, made of lead or any other material, for instance a plastic or elastic material. Said washers are intended to insure a water-tight joint between band 1 on the one hand, and the heads of the bolts and the nuts on the other hand.

It will be noted that the rolled edges of the bands insure a notable rigidity of said bands, and therefore make it possible to make them of very thin metals, which reduces the cost and the weight, while allowing the bands to be fitted exactly in position.

If the glasses are to be set upon sash irons whose flanges already have their edges raised in the shape of gutters, I may evidently dispense with lateral bands 2, 2.

While I have described what I deem to be a practical and efficient embodiment of my invention, it should be well understood that I do not wish to be limited thereto as there might be changes made in the arrangement disposition and form of the parts without departing from the principle of my invention, in the case, for instance of sash irons having another section than those shown in the drawing. Likewise the edges of band 3 might be given any suitable shape different from that shown in the drawing. They might, for instance, not be rolled up when the nature and the thickness of the metal of the band ensure both the elasticity and the rigidity that are required.

What I claim is:

1. A device for securing a glass to a sectional

110

sash iron having a web and a flange substantially at right angles to said web, which comprises in combination, an elastic metallic band applied flatwise against said web and bent substantially at right angles so as to be also applied flatwise against said flange, the edge of the portion of the band that is applied against said flange being curved so as to form a rolled part interposed between said flange and said glass and bearing tangentially against said glass, a second elastic metallic band a portion of which overlaps said first mentioned band and the outer portion of which is bent so as to extend obliquely to said web, the edge of said outer portion being curved so as to form a rolled edge located opposite the rolled edge of the first mentioned band, whereby the glass can be elastically held between said two edges, and adjustable means for fixing said two bands to said web.

2. A device for securing a glass to a sectional sash iron having a web and a flange substantially at right angles to said web, which comprises in combination, an elastic metallic band applied flatwise against said web and bent substantially at right angles so as to be also applied flatwise against said flange, the edge of the portion of the band that is applied against said flange being curved so as to form a rolled part interposed between said flange and said glass and bearing tangentially against said glass, a second elastic metallic band a portion of which overlaps said portion of the first mentioned band that is applied against said web and the outer portion of which is bent so as to extend obliquely to said web, the edge of said outer portion being curved so as to form a rolled edge located opposite the rolled edge of the first

mentioned band and adapted to bear tangentially against said glass, whereby the glass can be elastically held between said two edges, a bolt extending throughout said bands and said web, and a nut screwing on said bolt for adjustably fixing said two bands to the web of the sash iron.

80

3. A device for securing to an inverted T-shaped sash iron two glasses extending on either side of the web of said iron, which comprises in combination, two lateral elastic metallic bands applied flatwise against the sides of said web respectively and bent substantially at right angles so as to be also applied flatwise against said flange on either side of said web respectively, the edge of the portion of each of

85

said bands that is applied against said flange being rolled up so as to form a curved part interposed between said flange and said glass and bearing tangentially against said glass, and an

90

elastic metallic band the central portion of which overlaps said bands and said web, the outer portions of the last mentioned band being bent so as to extend obliquely to said web, the

95

edges of said outer portions being rolled up opposite the rolled edges of the two first mentioned bands respectively and being adapted to bear tangentially against said glass, whereby the glass can be elastically held between said

100

two edges, and bolts extending throughout said web and said bands for adjustably securing these three bands to said web part of the last mentioned band to said web and applying its

105

sides against the sides of said web.

4. A device according to claim 3 in which the bolts are provided with washers of a soft material for insuring water-tightness.
